UNITED STATES PATENT OFFICE.

PHILIP J. SKULEY AND STEPHEN H. MEKULICH, OF TACOMA, WASHINGTON.

DOOR-OPENING DEVICE.

Application filed September 24, 1924. Serial No. 739,492.

This invention relates to mechanism for automatically opening and closing doors, gates, or the like, and more particularly to mechanism of that character used in connection with the doors of a garage whereby the weight of a vehicle, as it approaches the entrance, is utilized to swing the doors from closed to open position so that there is no need of the doors being manually opened.

Another object resides in the provision of means whereby the doors may be automatically opened when the entrance is approached by a vehicle either in entering or leaving the garage.

A still further object is to provide means for closing the doors after a vehicle has entered or departed from the garage and for locking them by means that may be released by a lever located outside the garage at a position where it can be easily reached by a person in a vehicle as it approaches the entrance.

Other objects of the invention reside in the various details of construction and combination of parts embodied by the invention and in their mode of operation.

In accomplishing these and other objects of the invention, we have provided the improved details of construction, the preferred forms of which are illustrated in the accompanying drawings, wherein—

Figure 1 is a perspective view showing the entrance of a garage equipped with doors adapted to be operated by mechanism constructed in accordance with the present invention.

Figure 2 is an enlarged plan view of the door opening and closing mechanism, showing parts of the garage in horizontal section for better illustration.

Figure 3 is a horizontal sectional view taken for the most part on the line 3—3 in Figure 2.

Figure 4 is a vertical, sectional detail showing one of the door locking devices and its connection with the control lever.

Referring more in detail to the several views of the drawings—

1 designates what may be a garage, or the like, having an entrance 2 equipped with doors 3—3⁷ that are hinged, as at 4, to the outer vertical edges of the entrance to swing outwardly to open position against stops 5 fixed to the floor or approach in front of the entrance.

Located respectively within the corners of

the garage, at opposite sides of the entrance as is best shown in Figure 2, are vertical guide housings 6—6' in which weights 7—7' are suspended from cables 8—8' which extend upwardly over sheave wheels 9—9' at the upper ends of the guide housings and sheave wheels 10—10' fixed to the lintel 11 across the top of the entrance and are attached at their ends, respectively, to the swinging edges of the doors 3—3' as a means of closing the latter after a vehicle has entered or left the garage. These weights 7—7' are of sufficient weight also to move the door opening mechanism, presently described, back to normal position after a door opening operation.

Continuing from the floor 15 of the garage at the front thereof is a platform, or approach, 16 that overlies a pit 17 and supported flush with the surface of the platform in parallel openings 18 and 18' which extend from near the outer edge of the platform substantially into the garage, are runway planks 19—19' and 20—20'; the planks 19—19' being arranged in pairs with the planks 19—19' supported hingedly at their outer ends by hinges 21 from the outer ends of their openings and resting at their inner ends on a transverse beam 22, while the planks 20—20' are hingedly supported at their inner ends by hinges 23 from the inner ends of the openings 18—18' and at their outer ends rest upon the transverse beam 22. These openings 18—18' are spaced apart a distance equal to the standard spacing of the opposite side wheels of an automobile and are so located with respect to the garage entrance that a vehicle may travel into or from the garage on the runway planks.

At its opposite ends the transverse beam 22, above mentioned, is supported upon lever beams 25—25' which are arranged in the pit 17 in parallel relation to the runway planks 19—19' and which are pivotally supported at their inner ends upon a transverse beam 26 that extends beneath the floor 15 of the garage just back of the inner ends of the openings 18—18'. Fixed to the outer ends of these lever beams, in spaced relation longitudinally thereof, are sheave wheels 27 and 28 and fixed to the under side of the platform 16 in alignment with but between the sheaves 27 and 28 are sheave wheels 30, 31 and 32 (see Figure 3) and extended respectively over the sheaves of the two levers are cables

31 and 31' which have ends attached to the under side of the platform, as shown at 32 and which extend upwardly, after passing over the sheaves 27, within hollow columns 5 33-33' erected at opposite sides of the runway and over sheave wheels 34-34' mounted within the upper ends of the latter and then are extended, as shown in Figure 2, to the doors to which they are respectively attached by the anchor bolts 35-35', the inner ends of which may be used for attaching the cables 8 and 8'.

With this construction, the weights 7-7' through the cables 8-8' normally retain the 15 doors closed, and through cables 31-31' support the lever beams 25-25' in such position that the runway planks are held flush with the platform and floor of the garage. When the runway planks have been lifted to 20 this flush position they cannot be raised higher for the reason that the cross beam 22 engages with the under side of the platform and the doors are closed against a stop 36 provided along under side of the lintel 11.

25 Should a vehicle be driven onto the outer runway planks 19-19', its weight will cause the planks to be pressed downwardly, as shown in dotted lines in Figure 3, and thus the cross beam 22 causes the lever 30 beams 25-25' to be moved downwardly and the cables 31-31' to be drawn down and the doors to be swung open and against the stop blocks 5-5'.

35 After the vehicle has passed into the garage, the weights 7-7' acting through cables 8-8' draw the doors closed and lift the runway planks to normal position.

40 The same action takes place should the vehicle move from within the garage onto the inner runway planks 20-20' and the doors will be held open until the vehicle has passed from the outer runway planks.

45 To add rigidity to the column structure, the latter are connected across their upper ends by a cross beam 40 and if it is necessary other suitable bracing could be provided to withstand the pull of the cables that lead from the upper ends of the columns.

50 We have also provided a locking mechanism for the two doors and have provided means whereby the locks may be released by a person in a vehicle approaching the entrance. The mechanism preferably would be as follows: Fixed to a transverse beam 42 below the entrance to the garage are guide 55 housings 43 in which lock bolts 44 are slidably held; the latter being adapted to lock within strap loops 45 fixed to the lower edges of the doors, as shown in Figure 4, and are yieldably held in locked position by means of springs 46 attached at their ends to the bolts and their housings. To the lower ends of the locking bolts are attached cables 48-48' which extend downwardly 60 and about guide rollers 49 and then beneath

the platform toward its forward end where they are attached to arms 50-50' on a cross shaft 51 rotatably mounted in supports 52. Fixed to one end of the shaft 52 and extended upwardly through an opening 53 70 in the platform is a lock release lever 54 provided with a slot 55 for receiving a loop 55' fixed to a standard 56 that is rigidly mounted on the platform adjacent the runway. A padlock 58 may be used to lock the 75 lever to the standard. When it is desired to unlock the doors, the padlock is removed and the lever 54 swings outwardly to thereby rotate shaft 51 to draw on cables 48-48' and thereby release the locking bolts from 80 the doors.

It is readily apparent that by such construction, the doors can be automatically opened and closed and thus a driver of a vehicle is not required to get out and open 85 and then close the doors when entering or leaving the garage.

It is further apparent that various changes in the details of construction and combination of parts could be made without departing from the spirit of the invention and for this reason we do not wish to be limited only to the details herein shown.

Having thus described our invention, what we claim as new therein and desire to secure 95 by Letters Patent, is—

1. The combination with a building having a vehicle entrance and doors hingedly mounted in said entrance to swing outwardly from closed to open position, of yieldable means for normally retaining the doors closed, a floor for the building and an approach to the entrance continuing from said floor having parallel openings therein leading into the building through said entrance, a cross beam disposed below said approach, two runway planks disposed end to end in each of said openings having their outer ends pivotally supported at the opposite ends of said openings and their adjacent inner ends supported on said cross beam, a pair of levers disposed parallel to the runway planks and beneath the beam to support the cross beam, means pivotally supporting the inner ends of said levers, and cables attached to the doors and having operative connection with the said levers whereby downward movement of the latter, incidental to the weight of a vehicle on the runway planks, will cause the doors to be 115 opened.

2. The combination with a building having a vehicle entrance and a pair of doors hinged to the opposite sides of said entrance to swing outwardly from closed to open position and stops for limiting the opening and closing movements of said doors, of cable guides within the building, weights and suspending cables attached to said weights and passing over said guides and attached to 125 130

said doors for yieldably retaining them in closed position, an approach platform to the entrance and a continuing floor in said building having openings therein leading in 5 paralleled relation through said entrance, a pair of lever beams disposed parallel with the said openings and extended from within the building outwardly beneath the approach, pivotal supports for the inner ends 10 of said levers, a cross beam beneath the approach supported at its ends on said levers, a pair of runway planks disposed end to end in each of said openings, pivotally supported 15 at their outer ends with their adjacent ends

resting on said cross beam, a pair of columns 15 erected at opposite sides of the approach, sheaves at the upper ends of said columns, sheaves on the outer ends of said levers and cables attached to the doors and passing over 20 said column sheaves and lever sheaves and attached to the platform whereby downward movement of the levers incidental to the weight of a vehicle on the runway planks will cause the doors to be opened.

Signed at Tacoma, Pierce County, Wash- 25
ington, this 7th day of August 1924.

STEPHEN H. MEKULICH.

PHILIP J. SKULEY.
